UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,325,803.

Specification of Letters Patent. Patented Dec. 23, 1919.

Application filed January 17, 1916. Serial No. 72,482. Renewed May 15, 1919. Serial No. 297,413.

To all whom it may concern:

Be it known that I, FRANK C. RINSCHE, a citizen of the United States, residing at Detroit, in the county of Wayne and State 5 of Michigan, have invented certain new and useful Improvements in Adding-Machines, of which the following is a specification.

The present invention relates particularly to the equipment of an adding and listing machine for facilitating the handling of ledger sheets and the like. In a prior application filed September 19, 1914, Serial No. 862,593, I have shown, described and 15 claimed an equipment of this sort which involves the employment of a platen in the form of a segment of a cylinder, in place of the customary roller platen. The platen of this prior construction is relatively flat, the 20 object being to provide for printing upon it by ordinary printing mechanism of an adding machine, without so far bending the inserted sheets as to affect the flat form in which they must be handled. This same 25 characteristic is present in the improved construction of this application though I have found it practicable to employ a segmental platen of shorter radius and I have adopted such in the present instance to insure 30 clean and sharp printing under a rearrangement of the printing mechanism of the machine proper by which provision is made for "visible" printing. In this same connection I now dispense with the mounting 35 of the segmental platen in a cradle or recking support, and mount it in fixed bearings upon the laterally shiftable carriage of the machine. According to the general plan of my prior invention, the platen of 40 the present construction is arranged to swing up and down and the sheet to be printed upon is placed in position upon the platen when the latter is in its uppermost position, and the platen is then lowered to 45 the proper position for printing upon the top line of the sheet and is afterward fed up step by step as the work proceeds, with or without intervening columnar shifts of the carriage. In the prior construction the 50 clamping of the inserted sheet in position against the platen was accomplished by separate manipulation of a clamp-handle. In the present instance clamping of the sheet is done automatically as an incident to the 55 lowering of the platen, and correspondingly

the unclamping and release of the sheet for removal occurs automatically as an incident to the rise of the platen to its uppermost position. For the purpose of regulating the extent of lowering the platen to the proper initial position to suit the work in hand, I provide an adjustable stop which can be set at any location desired within a large range of movement so as to definitely insure uniform positioning of inserted sheets according to linear requirements of the accounting work in hand.

A further departure from the prior construction is to be found in the mechanism for line-spacing. Instead of employing gear wheels in mesh with racks on the back of the platen and applying ratchet and pawl action to the gear wheels, I mount a segmental ratchet on the back of the platen and I employ a reciprocating pawl which is normally held in engagement with the ratchet by a spring. I also employ a retaining pawl likewise held in engagement with the ratchet by a spring, and, as a matter of increased facilities for manipulating the platen, I provide a third pawl to engage the ratchet so that manual line-spacing of the same may be had at will; it being understood that the first mentioned pawl is reciprocated through mechanical connection with the operating mechanism of the machine proper. These several pawls must of course be disengaged from the ratchet when the platen is to be lowered, and I make provision for simultaneously disengaging them by a manual act 85 easy and convenient of execution by the fingers of the hand of the operator while grasping a handle by which the platen is lowered. This same handle serves for elevating the platen independently of the line-spacing mechanism, and I further utilize it in connection with lateral positioning of the platen. Thus through the same connections by which the above mentioned pawls are disengaged from the ratchet, I provide for throwing off the tabulator stops carried by the laterally shiftable carriage as usual, so that the operator, having grasped the handle and applied finger pressure to said connections, may then shift the carriage any extent desired without obstruction by the tabulating devices. I preferably provide a settable element in the throw-off connections so that when desired, as when the machine is being used for mere listing or single col 100 105 110

umn work, the tabulator throw-off action may be eliminated while the line-space throw-off action is preserved.

With the above indicated objects in view, 5 as well as others of minor or incidental character, my present invention consists in certain novel constructions and combinations of parts, hereinafter claimed. A preferred form of embodiment is illustrated in the accompanying drawings and that I shall proceed to specifically describe.

Of said drawings Figure 1 shows the ledger sheet carriage in right side elevation, mounted upon a machine, a portion of whose 15 casing appears in section together with some of the internal mechanism in elevation; Figs. 2 and 3 are enlarged detail sectional views taken on lines 2—2, 3—3 of Fig. 1; Fig. 4 is an enlarged detail sectional perspective of parts at the left of the platen; Fig. 5 is a rear elevation with some parts broken away and in section; Fig. 6 is a perspective view looking from the rear and showing parts at the right hand side of the 25 platen; Fig. 7 is a vertical section taken on the line 7—7 of Fig. 5; Figs. 8 and 9 are sectional details taken on lines 8—8 and 9—9 of Fig. 7; Fig. 10 is a vertical section taken on the line 10—10 of Fig. 5; Fig. 11 is a partial left side elevation; and Fig. 12 is a similar view illustrating the effect of elevating the platen beyond the position shown in Fig. 11.

Referring first to Fig. 1, the reference figure 35 611 designates one of a series of levers on the order of those so familiar in the Burroughs adding and listing machine, which levers carry the adding racks at their forward ends, and the printing types at their 40 rear ends. In the present instance these levers do not have type-carrying segments integral with them, but they have studs which occupy slots in vertical type-carrying bars 612, each bar having a series of ten types 45 618 suitably mounted in a housing at the upper end of the bar. The purpose of departing in this way from the usual arrangement in a Burroughs machine, is to provide for "visible" printing. Thus the type-carrying bars are adapted to be projected upward through an opening in the top of the machine, and after the printing has been done, these bars retreat to expose the imprint. Inasmuch as this modification does 50 away with an arcuate arrangement of types, I find it desirable to shorten the radius of the segmental platen, as compared with that of my prior construction which was designed for use with the standard Burroughs machine. The platen is designated by the numeral 2 and is composed of a sheet of metal, rubber faced. In my former construction a similar sheet of metal was confined in curved guides mounted upon the cradle of the laterally shiftable carriage. In the present in-

stance the platen has radial arms 2^a which unite in the split hubs 2^b, clamped upon a tubular shaft 2^c, which is suitably journaled between the side pieces 3 of the laterally shiftable carriage. The latter is mounted 70 in the customary way upon the back of the machine. The numeral 4 designates the customary track on which the carriage runs. The numeral 5 designates the hinged back panel of the machine casing to which the 75 track is secured. Adjustment for the purpose of securing the right spacing of the platen from the type is provided for by the hollow screws 5^a on said panel and locking screws 5^b running through the hollow 80 screws and into bosses on the machine frame. (Fig. 9.)

The segmental platen is adapted to oscillate between limits about the axis of its journal-mounting in the carriage, and in view 85 of its size and its weight and that of various parts it carries, I preferably employ a counterbalancing spring 7 which is coiled about the hollow shaft 2^c at the right hand end thereof as the parts are seen in Fig. 5, 90 said spring being anchored at one end in the adjacent side piece 3 of the carriage, and engaged at its other end with an arm 2^d which is fastened to the said shaft. The only function of this spring is to counter- 95 balance the weight tending to lower the platen. Normally the platen would be upheld by the pawls hereinbefore mentioned which engage the ratchet on the platen (all of which parts will be specifically identified 100 later on), but it is desirable that the platen with the parts carried by it, aggregating considerable weight, be not at any time free to drop, entailing shock and danger of possible damage to the machine.

Referring next to the matter of introducing the sheet to be printed upon, and gaging that sheet and clamping it in proper position; there extends across the full width of the platen at the lower edge thereof at the 110 front side, a plate or bar 8, which is formed with hinge ears receiving a pintle 9 also engaged with hinge brackets 2^e fastened to the platen. (Fig. 5). Said plate is bent at right angles to form a horizontal shelf or ledge 115 8^a just below the bottom edge of the platen. A front portion 8^b of said plate extending vertically from the ledge, and being of appreciable height, constitutes a clamp for holding a sheet of paper securely against 120 the face of the platen when said sheet has been dropped thereover and rests upon the ledge. Referring to Fig. 12, the hinged plate or bar is there shown thrown forward to receive the sheet S dropped over the face 125 of the platen. The plate or bar is so held in opposition to a spring (presently identified) which tends to swing it rearward to the position shown in Fig. 11, and also in Figs. 7 and 10. In Fig. 4 the condition is 130

the same as that represented in Fig. 12. At its left hand side the plate has a rearwardly turned ear ^{8e} to which is pivotally connected a link 11. This link extends rearwardly and is pivotally connected to one arm of a bell-crank lever 12 pivoted upon the before mentioned arm ^{2d}.

A spring 13 coiled around the hub of the bell-crank lever 12 serves to throw the gaging and clamping plate rearward, said spring being anchored at one end in the bell-crank lever and at the other in arm ^{2d}. It will be recalled that the latter is fixed to the platen hub ^{2b}. Hence, in the absence of any interfering factor, the bell-crank 12 and link 11 would simply move with the platen and have no individual movement of their own, in which event the condition would always be that illustrated in Fig. 11, and that is the condition whenever printing is in progress or the inserted sheet is in readiness to be printed upon. However, when the platen is in its uppermost position the clamp must be open ready to receive a sheet, as in Fig. 12, and here other elements come into play. A bell-crank lever 14, pivoted upon the left hand side of plate 3 of the carriage, has a rearwardly extending arm with a contact head ^{14a} to operate upon the forwardly extending arm of the bell-crank 12, and a forwardly and upwardly extending arm formed with a hump ^{14b} adapted to coöperate as a cam with a roller ^{2f} on the side of the platen. The latter has a series of reinforcing ribs running up and down its back and the roller is conveniently mounted upon the left hand one of these ribs which is designated ^{2e}. When the platen is moved upwardly beyond the last position in which printing is done, said roller operates upon the cam-hump ^{14b}, rocks the bell-crank 14, and thereby the bell-crank 12, so that the latter thrusts forward link 11 and the gage and clamp plate is swung forward to release the sheet or make ready to receive a sheet dropped over the face of the platen. The bell-crank 14 is limited in its movement by a stud ^{3e} on the carriage side-plate (Fig. 10) and, besides serving as a clamp-opening medium, also serves to limit the upward movement of the platen. To this end the extremity of the upwardly extending arm of the bell-crank takes the form of a hook ^{14c} in which the roller ^{2f} seats as shown in Fig. 12.

Starting with the condition illustrated in Fig. 12, the sheet ^S is dropped over the face of the platen and lands upon the gage and clamp-plate, the edge of the sheet seating in the angle of the ledge ^{8a} and the clamp-plate ^{8b}. This squares the sheet so it is immediately ready to be clamped against the face of the platen. Upon lowering the latter, and before or just as it reaches a position

opposite the type, the roller ^{2f} passes down beyond the cam-hump ^{14b} and the spring 13, at once throws the gage and clamp-plate rearwardly and the sheet ^S is securely clamped against the face of the platen while still resting squarely upon the ledge ^{8a}, as clearly illustrated in Figs. 7 and 10. I utilize the forward portion of the link 11 as a side-edge gage for the sheet by extending it above and below the point of pivotal connection with the clamp-plate ⁸, thus forming a sort of T-head ^{11a}, which extends closely adjacent the side of the platen as best shown in Fig. 4. The ear ^{8e} of the clamp-plate is in a position to serve as a side edge gage for the sheet, but it is preferable to have more extended gaging means such as supplied by the above described formation of the forward end of the link 11.

It is desirable that a warning signal be given the operator to show when the lower end of the sheet is approaching the printing line. I utilize the lower arm of the bell-crank lever 12 for such purpose, the end of the said arm being adapted to wipe past the nose of the trip piece of a bell mechanism of familiar character mounted upon the side plate of the carriage. Such sheet-end warning bell mechanisms are so well known in this art that it is unnecessary to describe in detail that herein shown. The bell is designated by the numeral 15 and the relation of its striker mechanism to the bell-crank 12 may be such that the warning will be given when the platen rises to a position two lines short of the final printing position.

Referring next to the matter of adjustably limiting the lowering of the platen, there is secured to the rib ^{2g} of the latter a stop-piece ^{2h} Fig. 5 which is adapted to abut against the laterally-turned end-portion ^{16a} of an arcuate bar 16 extending along side the carriage side-plate 3 and integral with a radial arm ^{16b} journaled upon the rod ^{3d} about which the tubular shaft ^{2e} or platen-hub turns, said rod being suitably fastened in the carriage side plates. The arcuate bar 16 is slotted throughout the greater portion of its length and a stud ^{3e} on the side plate 3 occupies the slot and receives a thumb nut 17 by which the said arcuate bar can be clamped in any desired position. Obviously this provides for setting the bar to limit the descent of the platen to suit the work in hand. The adjustment fixes the uppermost printing line and where a number of sheets are in use calling for uniformity in this regard, or the same sheet is to be inserted repeatedly for printing in different columns beginning along the same line, uniformity in this regard will be insured without the operator's being called upon to give close attention to adjustment of the platen each time.

Besides the provision of the clamp-plate to secure the lower end of the sheet, it is desirable to supply means for laying the sheet smoothly back over the face of the platen, and it is particularly desirable that the sheet be held closely against the platen at the printing point. A thin vertical plate 5^a is secured to back panel 5 of the machine, and extends closely adjacent the platen 10 along the printing line, being cut out at the middle of its upper edge in a width corresponding to the cross-wise line of type. The inking ribbon 20 intervenes, as shown in Fig. 1, spanning this cut-out portion of 15 said plate and extending above the latter, it being understood of course that the type normally stand below the printed line. As the platen lowers from its uppermost position, the sheet is first carried past the upper 20 edge of this thin plate 5^a. A short distance below the top edge of said plate, the top edge of a curved plate 22 meets the rear face of plate 5^a as clearly shown in Fig. 10, said curved plate conforming with 25 the platen and extending in proximity to the face thereof. This curved plate is fastened to the carriage and extends considerably to the rear thereof so that when the platen is in its lowermost position the 30 clamp-plate 8^b is just beyond the rear edge of the curved plate which is slightly down-turned as shown in Fig. 7 to avoid any possible interference with the clamp. A pressure roller 23 occupies a cut-out portion 35 of the latter plate at its rear edge, as shown most clearly in Fig. 5, and is adapted to bear against the platen when so lowered, and a similar pressure roller 24 occupies an opening in the upper forward portion of 40 the plate. These two pressure rollers are supported respectively in pairs of arms 25 pivoted to brackets fastened on the underside of said plate 22, said arms being connected together by springs 26 which press 45 the rollers against the platen. In addition to the above described means for laying the sheet back over the platen and holding it flat against the same, there is preferably located at the opening in the machine 50 through which the type rise, a yoke 30 pivoted to brackets 5^c and spring-pressed rearwardly so as to exert pressure upon the paper on both sides and above the area in which the printing is done.

55 Passing now to the means for line-spacing, which involves propelling the platen step by step upward, there is secured against the back of the platen at the right hand side inward from its margin a ratchet segment 40, 60 as best shown in Figs. 5 and 6. The reference number 41 designates the pawl which operates upon this ratchet to automatically effect line-spacing in conjunction with operation of the adding machine. This pawl 65 is pivoted upon a short crank arm 42 se-

cured to a rock shaft 43 which has another short crank arm 44 secured to its opposite or outer end. A link 45 connects the crank arm 44 with a slotted crank plate 46 of familiar character, said plate being secured 70 to the rock shaft 48 of the line-space bail which is so familiar in this class of machine as to require no specific description. It is oscillated by the prime mover of the machine, through connections of the usual character, and it will be obvious that the pawl 41 will be reciprocated through the described connections between it and said bail. Spring 49 enforces engagement between the pawl and the ratchet. The rock shaft 43 is preferably journaled eccentrically in a bearing 50 adjustably mounted in the carriage side plate 3 as shown in Fig. 2, so as to provide for insuring the proper coaction between the pawl and the ratchet. At the lower part of 80 the ratchet segment there is a plain surface 40^a, best shown in Fig. 7, the purpose of which is to stop the line-space action when the platen reaches the uppermost printing position. It will be understood that when 85 the handle of the adding machine is pulled forward, the pawl 41 is drawn back over a tooth of the ratchet and then when the machine handle is released and the operation of the machine continues under the power of 90 its main springs, the pawl advances and pushes up the platen, carrying the imprint above the inking ribbon. It is preferable to employ a detaining pawl to uphold the platen during the retraction of the actuating 95 pawl. The reference numeral 52 designates such a detaining pawl which engages the ratchet tooth next above that which the actuating pawl normally engages. This detaining pawl is secured to a pivot pin or 100 stud 53 journaled in a bearing sleeve 3^c fastened in the carriage side plate 3 as shown in Fig. 3. A spring 54 connects the pawl with a stud on said side plate to enforce engagement of the pawl with the ratchet. 105

In connection with the description of the means for automatically clamping and releasing the sheet, reference was made to movement of the platen beyond the last position in which printing is done. It will 110 be understood that the sheet should not be released until after the last printing has been done. Now in practice, when the feed pawl 41 has operated upon the lowermost tooth of the ratchet and has retired to the plain surface 40^a, the operator, in order to release the sheet, lifts the platen by hand (using the knob 71 hereinafter described), and the opening of the sheet-clamp occurs 115 in the manner before described. While this is occurring, the said plain surface 40^a, rides past the feed pawl 41 and the detaining pawl 52. Beyond said plain surface there is a notch 40^b into which the detaining pawl enters as the limit of upward movement of 120 125 130

the platen is reached, so as to detain the latter in the uppermost position with the clamp open for the reception of another sheet.

For the purpose of definitely line-spacing 5 the platen by hand as occasion may require, I provide a third pawl 60, having a pivot portion 60^a (Fig. 3) journaled in the sides of a yoke 61 mounted upon the sleeve bearing 3^c. A pin 62 running through the pintle 60^a and a surrounding sleeve 63 which confines the pintle, serves as an anchorage for one end of a spring 70 coiled around the sleeve bearing 3^c and secured at the other end to the yoke 61, said spring enforcing 10 engagement between the pawl 60 and the ratchet. One side of the yoke 61 is extended upwardly and bent laterally to form a handle 61^a conveniently located for the application of finger pressure to rock the yoke and 15 thereby line-space the platen by hand. Stud 65 on the carriage side plate occupies a notch in one side of the yoke for the purpose of limiting its rocking motion.

In order to move the platen downward 20 beyond the final printing position, it is of course necessary to disengage the above described pawls from the ratchet. I provide for conveniently accomplishing this and easily maintaining the disabled state of the pawls 25 while moving the platen up or down, all by simple manipulation effected with one hand in a perfectly natural manner. A rod 80, Fig. 6, runs through and is locked to one of the radial arms 2^a of the platen, and also 30 runs through the right hand one 2^b of the reinforcing ribs on the back of the platen, and out beyond the platen. This rod supports a knob 71 which serves as a handle for raising and lowering the platen. A 35 sleeve 72 is mounted upon this rod to slide between the platen rib 2^b and the knob, and this sleeve at the end adjacent the knob carries a cup-shaped finger pull 72^a so that the operator, while grasping the knob, may 40 readily embrace the sleeve between two fingers and exert a pull upon the same by finger pressure on said pull-piece. A lever 73 is pivoted intermediate its ends in a small bracket 2ⁱ carried by a rearward extension 45 of the platen rib 2^b. This lever has a fork at the forward end embracing the sleeve 72 adjacent a collar 72^b formed thereon. Said 50 lever has a fork also at its rear end which embraces a sleeve 75 sliding upon the platen 55 hub 2^c. The inner end of this sleeve 75 is embraced by the fork 76^a of a bell-crank lever 76 pivoted to a bracket 3^b fastened to the carriage side-plate 3. Said bell-crank lever is connected by a link 77 to a crank- 60 arm 78 on a short rock shaft 79 journaled in a bearing on the said carriage side-plate. Stud 78^a on said crank arm 78 normally 65 seats in the bottom of a notch in an arm 80^b pivoted upon a stud 3ⁱ carried by the carriage side-plate. Said arm 80^b has a for-

wardly projecting finger 80^a, which is turned upwardly and extends in front of all three of the before described pawls 41, 52 and 60. A spring 85 connects the crank arm 78 with the frame stud 3ⁱ, which spring holds the parts in normal position with the upturned portion of the finger 80^a forward of the pawls and the finger pull 72^a retracted. Upon applying pressure to said finger pull the arm 78 will be pulled upward and its stud 78^a will act against the rear side of the notch in the arm 80^b, and force this arm rearwardly and cause the finger 80^a to press the three pawls out of engagement with the ratchet.

I provide for action of the finger pull 72^a in excess of what is required for disengaging said pawls from the ratchet but without further retracting the pawls, the excess movement being transmitted only to the 85 crank arm 78 whose stud, after operating with the camming effect upon the rear side of the notch in the arm 80^b, may ride upon an upper inclined edge 80^c of said arm. This 90 excess movement of the crank arm 78 and its shaft 79 is utilized for the purpose of disabling the tabulator stop mechanism so that when desired the operator, through the use of the knob 71 and finger pull 72^a may obtain 95 control of the laterally shiftable carriage for positioning the same independently of said tabulating mechanism. For this purpose there is secured to the outer end of shaft 79 a depending arm 90 which is adapted, during such excess movement, to operate 100 on a pin 91. The latter runs through the upper end of an arm 92^a which is journaled upon the line-space bail shaft 48, and constitutes part of a yoke 92 which is a very 105 familiar element of the Burroughs machine. It serves to rock the shaft 93 which carries the familiar tabulating fingers 93^a. The excess movement of the finger pull 72^a therefore has the same effect as the rocking of the yoke 92 by its own handle 92^b, to-wit, the 110 effect of disabling the tabulating mechanism and permitting full lateral control of the carriage directly by hand.

Inasmuch as it may be undesirable at 115 times to have the tabulator mechanism subject to the action of the finger-pull 72^a, but desirable to have it left merely to individual disablement by the regular yoke handle 92^b, I make the pin or stud 91 shiftable into and out of line with the arm 90. Thus said pin 120 is mounted to slide through the extended side pieces of the yoke 92 and it is notched for coaction with a small detaining spring 95.

Shifting of this pin to the dotted line position illustrated in Fig. 5 would be desirable 125 where the machine was in use for listing or single column work when the operator might wish to employ the finger-pull for disabling the ratchet and pawl mechanism and swinging the platen up or down, without having 130

to pay any heed at all to the further function of that finger-pull to disable the tabulating mechanism, and release the carriage from its certain columnar position. In this connection it may be noted that provision is made for carrying a roll of narrow paper upon the rear side of the platen and threading it through the clamp and carrying it up over the face of the platen. Referring to Figs. 5 and 10, it will be seen that the rib 2^g and a similar rib 2^l provide bearings for a paper roll 97. Broken lines in Fig. 10 show how the paper can be drawn from the roll, threaded through the clamp and carried up over the face of the platen and under the clamp plate of a spring-held guide bracket 98, said plate overlying the upper edge of the platen and being serrated at its rear edge to serve for severing the paper when desired.

20 While the above described mechanism is well adapted to carry out my invention, it must be understood that much modification may be practised within the scope of that invention, and this is to be borne in mind in connection with the claims which follow.

I claim:

1. In a machine of the class described, the combination with printing means, of a platen facing the same in the form of a segment of a cylinder mounted to move in an arc of such cylinder, and having a ratchet extending along its back in rear of its face and within its lateral margin, and a reciprocating pawl acting upon said ratchet to elevate the platen step by step.
2. In a machine of the class described, the combination with printing means, of a platen facing the same in the form of a segment of a cylinder mounted to move in an arc of such cylinder, and having a ratchet extending along its back with teeth rearwardly and downwardly directed, and a reciprocating pawl acting upon said ratchet to elevate the platen step by step.
3. In a machine of the class described, the combination with printing means, of a platen facing the same in the form of a segment of a cylinder mounted to move in an arc of such cylinder, and having a ratchet extending along its back, a reciprocating pawl acting upon said ratchet to elevate the platen step by step, and a handle and connections operable to disengage the pawl from the ratchet and to serve for directly positioning the platen by hand.
4. In a machine of the class described, the combination with printing means, of a platen facing the same in the form of a segment of a cylinder mounted to move in an arc of such cylinder, and having a ratchet extending along its back, a reciprocating pawl acting upon said ratchet to elevate the platen step by step, a prime mover, operating connections between the same and said pawl, and an independent pawl also engag-

ing said ratchet and equipped for manipulation to effect line-spacing by hand.

5. In a machine of the class described, the combination with printing means, of a platen facing the same in the form of a segment of a cylinder mounted to move in the arc of such cylinder, and having a ratchet extending along its back, a reciprocating pawl acting upon said ratchet to elevate the platen step by step, a prime mover, operating connections between the same and said pawl, an independent pawl also engaging said ratchet and equipped for manipulation to effect line-spacing by hand, and a handle and connections operable to disengage said pawls from the ratchet and serve for directly positioning the platen by hand.

6. In a machine of the class described, the combination with printing means, of a platen facing the same in the form of a segment of a cylinder mounted to move in the arc of such cylinder, and having a ratchet extending along its back, a reciprocating pawl acting upon said ratchet to elevate the platen step by step, a laterally shiftable carriage, tabulating stop devices therefor, and a handle and connections operable to disengage the pawl from the ratchet and also to release the carriage from the tabulating stop devices.

7. In a machine of the class described, the combination with printing means, of a platen facing the same in the form of a segment of a cylinder mounted to move in the arc of such cylinder, and having a ratchet extending along its back, a reciprocating pawl acting upon said ratchet to elevate the platen step by step, a laterally shiftable carriage, tabulating stop devices therefor, and a handle and connections operable to disengage the pawl from the ratchet and also to release the carriage from the tabulating stop devices, said connections including a shiftable member whereby to eliminate the tabulator release action.

8. In a machine of the class described, the combination with printing means, of a platen facing the same in the form of a segment of a cylinder mounted to move in the arc of such cylinder, and having a ratchet extending along its back, a reciprocating pawl acting upon said ratchet to elevate the platen step by step, a laterally shiftable carriage, tabulating devices therefor, and a handle and connections operable varying extents, to disengage the pawl from the ratchet and by further movement to release the carriage from the tabulating stop devices.

9. In a machine of the class described, the combination with printing means, of a platen facing the same in the form of a segment of a cylinder mounted to move in the arc of such cylinder, and having a ratchet extending along its back, a reciprocating

5 pawl acting upon said ratchet to elevate the platen step by step, a knob on the platen, a finger pull adjacent the knob, a pawl-displacing member, and operating connections between the latter and the finger pull centered about the hub of the platen.

10. In a machine of the class described, the combination with printing means, of a platen facing the same in the form of a 10 segment of a cylinder mounted to move in the arc of such cylinder, and having a ratchet extending along its back, a reciprocating pawl acting upon said ratchet to elevate the platen step by step, a knob on 15 the platen, a finger pull adjacent the knob, a pawl-displacing member, operating connections between the latter and the finger pull centered about the hub of the platen, a laterally shiftable carriage, a tabulator-stop-rod thereon, and means for rocking the rod operable by the aforesaid finger-pull connections.

11. The combination of an open-top casting, type-carriers adapted to rise rectilinearly through said top to bring their type to the printing line and then retreat to leave the imprint visible, a platen in the form of a segment of a cylinder mounted opposite the type-carriers and movable up and down in an arc, means for positively limiting its movement in both directions, and means for receiving and holding up a sheet against the face of the platen.

12. The combination of printing mechanism; an oscillatory segmental platen; means for supporting and clamping a sheet thereon; and means for automatically operating the clamp as an incident to oscillation of the platen.

13. The combination of printing mechanism; an oscillatory segmental platen; a support and clamp for the bottom edge of a sheet overlying the platen; and means operated by the platen in its oscillation to 45 open and close the clamp.

14. The combination of printing mechanism; an oscillatory segmental platen; a support and clamp plate hinged to the platen and adapted to supply a ledge for 50 the sheet to rest upon and a means for clamping it against the face of the platen; and means operated by the platen itself for rocking said plate.

15. The combination of printing mechanism; an oscillatory segmental platen; a support and clamp plate hinged to the platen and adapted to supply a ledge for the sheet to rest upon and a means for clamping it against the face of the platen; 60 a spring tending to close the clamp; and means operated directly by the platen for opening it.

16. The combination of printing mechanism; an oscillatory segmental platen; a support and clamp plate hinged to the platen

and adapted to supply a ledge for the sheet to rest upon and a means for clamping it against the face of the platen; a spring-actuated lever adjacent the hub of the platen; a link connecting said lever with the 70 clamp-plate; and a lever to operate upon the first-mentioned lever and itself operated upon by the platen.

17. The combination of printing mechanism; an oscillatory segmental platen; a support and clamp plate hinged to the platen and adapted to supply a ledge for the sheet to rest upon and a means for clamping it against the face of the platen; a spring-actuated lever adjacent the hub of the platen; 75 a link connecting said lever with the clamp-plate; a cam lever arranged to operate upon the first-mentioned lever; and a stud on the platen for actuating the cam-lever.

18. The combination of printing mechanism; an oscillatory segmental platen, means for receiving and upholding a sheet of paper thereon, means for uniformly limiting the upward movement of the platen, and means for adjustably limiting its downward movement.

19. The combination of printing mechanism; an oscillatory segmental platen, means for receiving and upholding a sheet of paper thereon, means for uniformly limiting the 05 upward movement of the platen, a stop arm pivoted concentrically with the platen and having a slotted arcuate portion; and a thumb screw to hold the latter at different positions; said stop arm having a terminal 100 portion to coact with a stop projection on the platen.

20. In a machine of the class described, the combination with printing means, of a platen facing the same in the form of a segment of a cylinder mounted to move in an arc of such cylinder, and having a ratchet extending along its back with a plain terminal edge for causing cessation of line spacing, a reciprocating pawl acting upon said 105 ratchet to elevate the platen step by step, means for supporting and clamping a sheet on the platen, and means for opening the clamp by upward movement of the platen beyond the last position to which said pawl elevates it.

21. In a machine of the class described, the combination with printing means, of a platen facing the same in the form of a segment of a cylinder mounted to move in an 120 arc of such cylinder, and having a ratchet extending along its back with a plain terminal edge for causing cessation of line spacing and a supplementary notch beyond said edge, a reciprocating pawl acting upon said ratchet 125 to elevate the platen step by step, means for supporting and clamping a sheet on the platen, and means for opening the clamp by upward movement of the platen beyond the last position to which said pawl elevates it, 130

said supplementary notch then serving to uphold the platen.

22. In a machine of the class described, the combination with printing means, of a platen facing the same in the form of a segment of a cylinder mounted to move in an arc of such cylinder, and having a ratchet extending along its back with a plain terminal edge for causing cessation of line spacing and a supplementary notch beyond said edge, a reciprocating pawl acting upon said ratchet to elevate the platen step by step, a detaining pawl to engage said ratchet, means for supporting and clamping a sheet on the platen, and means for opening the clamp by upward movement of the platen beyond the

last position to which said pawl elevates it, said supplementary notch then serving to uphold the platen through coöperation with the detaining pawl.

23. The combination of printing mechanism; an oscillatory segmental platen; means for supporting and clamping a sheet thereon; means for automatically operating the clamp as an incident to oscillation of the platen; and means for line-spacing the latter with provisions for excess movement to open the clamp.
